(57) **CLAIM**

We claim the ornamental design for a medical sensor, as shown and described.

DESCRIPTION

FIG. 1 is a perspective view of the medical sensor of the present invention;

FIG. 2 is a top view of the medical sensor of FIG. 1;

FIG. 3 is a bottom view of the medical sensor of FIG. 1;

FIG. 4 is a right side view of the medical sensor of FIG. 1;

FIG. 5 is a left side view of the medical sensor of FIG. 1;

FIG. 6 is a front view of the medical sensor of FIG. 1; and,

FIG. 7 is a rear view of the medical sensor of FIG. 1.

The broken away symbols in the drawings indicate that any portion of the article beyond what is shown forms no part of the claimed design.

The thick broken lines in the figures are claimed features of the design. The thin broken lines in FIGS. 2 and 3 depict portions of the medical sensor that form no part of the claimed design.
